SKEW CORRECTING CIRCUIT

Francis F. Lee and Lawrence F. Harrison, Norristown, Pa., assignors to Sperry Rand Corporation, New York, N.Y., a corporation of Delaware

Filed Mar. 21, 1961, Ser. No. 97,353
19 Claims. (Cl. 340—174.1)

This invention relates to skew correcting circuits for the realignment of signal pulses read from a plurality of parallel channels of a storage medium, and more particularly, to apparatus providing buffer means for each channel to store a number of signal pulses successively read therefrom.

Information is often recorded on webs or tapes, thereby to provide temporary or permanent storage of the said information. Such information may, for instance, be recorded as magnetized spots, as holes in a web, or as optically observable marks; and in the process of recording, the web or tape is caused to pass adjacent a recording transducer whereby the transducer impresses the desired information on the web.

In many forms of information systems, this recording of information is accomplished in plural channels on the tape or web, and one of the major problems present in such a plural channel recording system is the maintenance of a constant spatial relationship between the recorded pulses. One method of achieving this constant spatial relationship is to utilize a multiple channel head comprising a plurality of spaced individual transducers in conjunction with a recording medium such as a magnetic tape; and such an overall recording system is capable of high speeds of operation while satisfying the requirement of constant spatial relationship between pulses.

When such a multichannel recording system is employed, a further problem is ordinarily presented, and this further problem comprises the maintenance of a constant relationship between the multichannel head and the tape itself. In recording systems of the type described, the storage member or tape is ordinarily caused to pass between guides adjacent the opposed sides of a recording head or transducer; and these guides function to assure, as nearly as possible, a predetermined positional relationship between the transducer and tape during the recording or reproducing step. In practice, however, it has been found that due to variation of tape width during manufacture, or due to wear on the tape guides, to warp and camber of the tape, and/or to distortion of the tape edge or guides, it is extremely difficult to achieve a perfectly constant spatial relationship between the tape and transducer. Inasmuch as the guides must be set to accommodate the greatest possible width of tape so that binding of the tape in the guides will not occur, the tape may be subject to some angular variation in the guides as it passes adjacent to the transducer. This possible angular variation of the tape relative to a recording or reproducing transducer is commonly known as tape "skew," and such skew may in fact be cumulative between an original recording operation and a subsequent reproducing operation, or when a tape recorded on one machine is read on another machine. Such skew, of course, poses one of the major difficulties encountered in multichannel systems of the type described, in that time misalignment of the plural recording or reproducing channels can occur; and the way in which this time misalignment may in fact occur cannot be predicted and will not be repeated from pass to pass.

It is therefore an object of the present invention to provide means whereby pulse groups recorded at high densities may be synchronized and realigned when sensed even though one or more of the pulses in different groups are arranged in overlapping patterns.

Another object of the present invention is to provide

2

means for determining when all component members of a pulse group have been sensed to thereby immediately make said group available for further use.

A further object of the present invention is to provide a skew correcting apparatus for the same units of a multichannel recording system, wherein a plurality of buffer register stages are provided for each channel having both parallel read-in thereto and read-out therefrom.

Yet another object of the present invention is to provide skew correcting apparatus for the sense units of a multichannel recording system, wherein a plurality of buffer register stages are provided for each channel having parallel read-in thereto and serial read-out therefrom.

These and other objects, advantages, and operation of the present invention will become apparent from the following description which is to be taken in conjunction with the accompanying drawings, in which:

FIGURE 1 shows in block form an embodiment of the invention having one mode of operation;

FIGURE 2 shows in block form an embodiment of the invention having a slightly different mode of operation from that shown in FIGURE 1;

FIGURE 3 illustrates a typical pulse pattern on a storage medium, together with a group of transducers skewed thereto;

FIGURE 4 shows the details of a first species of FIGURE 1;

FIGURE 5 shows details of a second species of FIGURE 1;

FIGURE 6 illustrates in tabular form the operation of FIGURES 4 and 5;

FIGURE 7 shows details of FIGURE 2;

FIGURE 8 illustrates in tabular form the operation of FIGURE 7; and

FIGURES 9, 10, and 11 show and explain the symbols representing certain logical gates used in the invention.

FIGURE 1 of the drawings shows in block diagram form the information and control signal paths within one embodiment of the present invention. The general description of FIGURE 1 is to be taken in conjunction with FIGURE 3, which shows the skewed relationship of a number of information characters whose binary bits are contained in parallel tracks on an elongated information storage medium 10, such as magnetic tape or the surface of a rotating magnetic drum. FIGURE 3 shows a typical store arrangement having four information tracks, each track storing corresponding order binary bits of a plurality of successive characters recorded on the medium, to be sensed or read by a corresponding transducers T₁ through T₄ positioned adjacent each track. For example, track 1 of the storage medium may contain each binary bit of the characters having the binary order significance of 2⁰. Tracks 2, 3, and 4 each contain binary bits of the successive characters having respectively the binary order significance of 2¹, 2², and 2³. The tracks shown in FIGURE 3 may have binary order significance other than that described, and the number of tracks thereshown may obviously be expanded or reduced, depending upon the number of unique characters to be stored. Transducers T₁-T₄ are positioned adjacent their respective tracks 1-4 so as to sequentially sense the binary bits found therein and convert same to electrical signals for use in the circuits hereafter to be described. In the event that the storage medium is of a magnetic nature, then the value of a binary bit stored thereon may be indicated by the direction of polarization of an incremental area of said medium, depending upon whether the binary bit value is a 1 or 0. On the other hand, many magnetic recording systems indicate a binary 1 bit by magnetization of an incremental area, while a binary 0 bit is indicated by the absence of magnetization. If other storage media

are utilized, such as punched tape or cards, then the presence of a perforation may indicate a binary 1. This invention is therefore not limited to any particular storage media or transducing system, but is useful wherever the bits comprising a character are in parallel but are not simultaneously sensed by all of the transducers associated with the information tracks.

In reading parallel channels from a record member, the reading transducer may not remain in the same fixed angular relationship with respect to said member as did the writing transducer. A change in this angular relationship between writing and reading therefore causes the parallel bits of a character to be read in skewed fashion, i.e., not simultaneously. FIGURE 3 shows an extreme example of character skew. The four binary bit positions astride the center line 12 comprise a character which is to be sensed by the transducers T₁-T₄. In like fashion, the four binary bits astride center lines 14, 16, 18, 20, 22, etc., comprise successive four bit characters which are to be sequentially sensed by the transducers. However, as may be observed from an examination of FIGURE 3, the center lines 12, 14, etc., are not parallel to the center line 24 of the transducer array. Assuming that relative motion between the transducers and the recorded characters is as indicated by arrow 26, it will be noted that the four bits comprising the character of center line 12 will not be simultaneously sensed by all of the transducers. For example, the track 1 binary bit of character 12 will be sensed prior to the sensing of the track 4 bit of character 12, with the track 2 and track 3 bits of character 12 being sensed in that order at times intermediate. In like fashion, the track 1 binary bit of character 14 is sensed prior to the sensing of its track 2, 3, and 4 binary bits, with the track 4 bits being the last to pass beneath its respective transducer T₄. Furthermore, FIGURE 3 illustrates a skew angle, i.e., that angle formed between the transducer center line 24 and the character center lines 12, 14, etc., which is great enough to result in the sensing of information binary bits of succeeding characters prior to the sense of the track 4 bit of a reference character. For example, when considering the character 12, it will be seen that the following information bits of succeeding characters are sensed prior to the sensing of the track 4 binary bit of character 12: the track 1 bits of characters 14, 16, and 18; the track 2 bits of characters 14 and 16; and the track 3 bit of character 14. In like fashion, when considering character 14 as a frame of reference, certain binary bits of characters 16, 18, and 20 will be sensed prior to the sensing of the character 14 track 4 bit. The decimal numbers found in parenthesis above each of the binary positions on medium 10 represent the sequence in which a particular binary bit is sensed by the array of transducers T₁-T₄. Thus, it will be noted that the track 1 bit of character 12 is the first to be sensed, followed by the track 1 bit of character 14, the track 2 bit of character 12, the track 1 bit of character 16, etc. FIGURE 3 shows an example whereby two or more information bits in two or more tracks are not sensed simultaneously by their respective transducers. However, it can be appreciated that a change in the skew angle may result in such a situation. Furthermore, it is to be noted that the binary bits comprising a character may not be recorded exactly on the character center line, but instead may fall to one side or the other thereof so as to result in a somewhat irregular pattern on the storage medium. The configuration shown in FIGURE 3, therefore, is implied for the purposes of the following description. However, the invention to be described may be employed in situations such as those discussed above without impairment of efficiency or operation.

Returning now to FIGURE 1, the information bit signals from each of the track transducers shown in FIGURE 3 are applied to respective channel input con-

ductors after passing through amplifiers and the like, said channel input conductors being represented by the dark face lines. Control signals are transmitted via conductors shown in light face lines so as to distinguish them from the flow paths along which the binary bit information from FIGURE 3 is transmitted. In FIGURE 1, only the first and last information channels are shown, with it being understood that there are as many information channels as there are parallel tracks on the storage medium being sensed. Furthermore, in order to show a more general system which may be used with a varying number of tracks, the first and last channels shown in FIGURE 1 are indicated as channel 1 and channel J, respectively, where the value of J is equal to the total number of channels present in the system. For sensing a storage medium having four tracks, therefore, J represents the value 4. All components are duplicated in each channel and have channel designating subscripts.

Referring specifically to the channel 1, it will be noted that the input conductor is connected to a plurality of read-in gates 30 which selectively direct a binary bit of information appearing thereon to one of a plurality of register storage stages 32. Since the binary bits transmitted to the channel 1 information conductor appear thereon in serial fashion, i.e., one behind the other, there will be only one information bit at any one time presented to the group of read-in gates 30. The selective conditioning of but one of the gates 30 is accomplished by a sequence circuit 34. After each binary bit has been inserted in one of the register stages 32, the sequence circuit 34 is changed so as to condition a different gate in group 30 to pass a subsequent information bit to a different register stage 32. Thus, as each information bit from track 1 appears on the channel 1 input conductor, it is placed in a respective register stage 30 and there awaits a readout signal, which only occurs when all of the bits of the character of which it is a part have been sensed by the transducers and placed in a respective register stage in each channel.

As each register stage 32 is filled with an information bit, one of a group of memory circuits 36 is actuated to indicate that the register stage has information therein. When a correspondingly numbered register stage in each of the channels has been filled, which occurs when every bit of a character has been sensed, then one of a group of comparison gates 38 detects equality of outputs from correspondingly numbered memory circuits 36 in all channels, in order to readout from the channel register stages the bits comprising a particular character. For this purpose, a group of read-out gates 40 are provided in each channel, with each read-out gate being associated with one of the register stages. The signal generated by a comparison gate in group 38 is applied only to a corresponding read-out gate in each channel so that only one register stage in each channel contains a bit of the same character. Therefore, even though a large skew angle results in the information bits of a particular character being read at widely varying times, with bits of succeeding characters being read at times intermediate, the output bits appearing on the channel conductors 42 all belong to the same character. Those information bits belonging to successive characters, which are read prior to the reading of the last information bit of a reference character, are stored in respective register stages of the channels until the entire character is stored in the skew correcting circuits, after which it is read and transmitted via conductors 42 to utilization circuitry not shown.

As shown in FIGURE 3, for example, four bits on track 1 are read prior to the sensing of the first bit on track 4. Thus, assuming that the system of FIGURE 1 contains four skew channels, it will be noted that four register stages of group 32₁ will be filled prior to entry of an information bit into a register stage of group 32₄. It is therefore seen that the first bit from track 1 must be

stored together with the three following track 1 bits until the first bit of track 4 is placed into a register stage of group 32₄. In addition, register stages in channels 2 and 3 (not shown) have also been filled with binary bits from tracks 2 and 3. After the first bit of track 4 is placed in its proper channel 4 register stage, then the first bits of tracks 1, 2, 3, and 4 may be read from their respective channel register stages, and these stages reset to await entry of a new information.

Each channel contains the same number N of register stages, which number depends upon the maximum number of information bits that any one of the channels must store between the times that read-out operations occur therefrom. In one species of FIGURE 1, the value N is equal to maximum number of skew bits. In a second species of FIGURE 1, the value N is equal to the maximum number of skew bits plus 2. Therefore, assuming that the information storage pattern of FIGURE 3 is being scanned where channel 1 must store 4 bits between read-out times, the first species of FIGURE 1 requires four register stages in each channel, while a second species requires six register stages in each channel. Therefore, the letter N is used in FIGURE 1 to indicate that its associated conductor is to be considered as a cable having N conductors therein. Thus, although the single input condenser 28 is applied to each of the N read-in gates 30, the output conductor 48 therefrom is to be considered as representing N conductors, each individual to one of the read-in gate outputs and individual to one of the N register stages 32. In like fashion, N output conductors 50 are individually connected between the register stages 32 read-out gates 40, whereupon of all of the outputs of read-out gates 40 are common to a single output conductor 42.

The means for stepping the sequence circuit 34 and setting memory units 36 may be provided by various schemes. The criterion here is to provide a synchronizing pulse to each channel each time that an information bit, whether binary 1 or binary 0, appears on the channel information input line 28. Each sync pulse causes a change in sequence circuit 34, and may also set a memory element. Synchronizing control pulses appearing on input conductor 32 may be generated from a synchronizing track associated with each individual information track on the storage medium. For example, in FIGURE 3, four synchronizing tracks (not shown) may be provided, each adjacent a respective one of the information tracks 1 through 4, in which appears a synchronizing 1 bit as at each information bit time. This scheme may be necessary where one of the two binary information values on the storage medium is represented by the absence of any mark thereon, or where certain non-return-to-zero recording procedures are used. In such case, a transducer T₁-T₄ will not generate a signal for one of the two binary bit values, but there will always be an indication in the adjacent synchronizing track for each value 0 or 1 which may be sensed by an adjacent synchronizing track transducer (not shown) such as to produce a signal on the sync conductor 32. Other schemes of generating synchronizing pulses for each binary bit time may be utilized, such as a variable frequency clock pulse generator whose repetition rate is adjusted by the frequency of the binary 1 bit signals read from the information track. Again, if binary 1 and 0 information bits are represented by oppositely polarized magnetic areas, then synchronizing pulses may be generated from the information signals.

FIGURE 4 shows the details of one species of the present invention having a mode of operation such as indicated in the block diagram of FIGURE 1. In this embodiment, the number of register stages in each channel is equal to the maximum number of skew bits desired to be stored in any of the channels between character read-out times. The circuitry for only two channels, the first and the last, is shown in FIGURE 4, although it is to be understood that this circuitry is duplicated for each of the

other channels. Subscripts are employed to identify a component *n* in channel *j*. In this and other figures where logical circuitry is utilized, symbols are shown to represent gates having certain logical functions which are well-known in the data processing and computing art. For example, as illustrated in FIGURE 9, a semi-circle with a dot therein represents an AND gate, while FIGURE 10 shows a semi-circle with a plus sign therein representing an OR gate. An AND gate detects coincidence between input signals applied to every input terminal thereof to generate an output therefrom. An OR gate, on the other hand, generates an output if one or more input signals are applied to its input terminals. If the junction of an input terminal with its gate is enclosed by a circle, such as is shown in FIGURE 10, then a signal on this terminal acts to inhibit an output from the gate.

In FIGURE 4, the register stages in each channel may comprise a group of trigger circuits S_{1j} through S_{Nj} each having set and reset input terminals respectively designated S and R. A signal is considered to appear on an output terminal from a trigger only if it is in its set condition. Other bistable storage means may be utilized and the invention is not to be limited by the structure specifically mentioned during the course of this description which is but exemplary of the art. Also associated with each register stage S_{Nj} is a bistable memory trigger M_{Nj} having set and reset inputs and an output on which appears a signal when the device is in its set state.

Information bits appearing on an input conductor 60_j are applied in common to a group of AND gates A_{1j} through A_{Nj} which in turn have outputs respectively connected to the said inputs of register stages S_{1j} through S_{Nj}. However, a bit appearing on conductor 60_j cannot pass through an AND gate A_{Nj} unless the other input thereto has a signal applied thereon. The signals for conditioning each of the AND gates A_{Nj} are provided by a sequence circuit C_j which may, for example, be a counter or a shift register. For each state C_j, one of its output lines *n* has a signal applied thereto which conditions its associated AND gate A_{Nj} to pass whatever information bit is present at this time on conductor 60_j. The circuit C_j is stepped each time that a sync pulse appears on conductor 61_j, so that each successive information bit appearing on conductor 60_j may be placed in different one of the register stages S_{Nj} in sequential order. Normally, the order of register stage filling proceeds from stage S_{1j} through S_{Nj}, and then back to S_{1j} again from whence the cycle repeats.

At the same time that circuit C_j conditions a respective one of AND gates A_{Nj} to pass an information bit it also conditions a respective one of the AND gates B_{Nj} associated with the set input of the memory element M_{Nj}. Each synchronizing pulse or conductor 61_j sets the memory element M_{Nj} which is associated with the register stage S_{Nj} being filled. Thus, each time a register stage S_{Nj} is filled with binary information, the corresponding memory element M_{Nj} is placed in its set condition.

It should be here noted that the embodiment shown in FIGURE 4 represents a binary 0 bit by the absence of a signal on conductor 60_j, which at the same time is accompanied by a sync bit on a conductor 61_j. For a binary 0 bit to be considered stored in a stage S_{Nj}, said stage must be in its reset state. Practically, this is accomplished by initially resetting all of the stages S_{Nj}, and then setting only those which must contain a binary 1 bit of information. When a binary 0 bit is to be stored, the register stage S_{Nj} having its AND gate A_{Nj} conditioned by circuit C_j will remain in its reset condition. However, since a synchronizing pulse always appears on channel 61_j for each information bit position no matter what the bit value, the memory element M_{Nj} having its AND gate B_{Nj} conditioned by circuit C is thereby placed in its set condition to indicate that the associated register stage S_{Nj} has been filled.

A group of AND gates D_1 through D_N are provided for comparing like numbered memory elements M_1 through M_N in each of the channels 1 through J, to determine when all of the compared memory elements are in their set condition. For example, AND gate D_1 has an input for each of the memory elements M_{11} through M_{1J} . These particular memory elements are those respectively associated with the first register stages S_{11} to S_{1J} in channels 1 through J. Thus, when all of the elements M_{11} through M_{1J} are in their set state, an output is generated from AND gate D_1 which indicates that register stages S_{11} through S_{1J} all contain information bits belonging to the same character. In like manner, AND gate D_2 determines when all of its associated memory elements M_{21} through M_{2J} are set, with gates D_3 through D_N having similar functions for the remaining sets of memory elements.

The outputs from each of AND gates D_1 through D_N are respectively applied to individual ones of a group of AND gates E_{1j} through E_{Nj} found in each channel. These gates are respectively associated with the outputs of individual ones of register stages S_{1j} through S_{Nj} . The function of a gate E_{nj} is to read-out the contents of its associated stage S_{nj} and to apply same to one of a group of OR gates F_1 through F_J . For example, when a signal is generated from AND gate D_1 , it is applied in common to all of the AND gates E_{11} through E_{1J} in order to sample the output terminals of respective stages S_{11} through S_{1J} . If one or more of these stages have previously been set by a binary 1 bit, then the associated AND gate E_{1j} will transmit a signal to the OR gate F_j where it appears on the output thereof. If a register stage S_{1j} is in its reset condition at the time read-out occurs, then no output appears on the associated OR gate F_j . This indicates that the stage S_{1j} contains a binary 0 bit.

At approximately the same time that a signal from an AND gate D_n is applied to the read-out gates of register stages S_{nj} in each channel, the same signal is applied via a small delay R_n and an OR gate G_{nj} to the reset terminals of stages M_{nj} and S_{nj} . This resetting operation is performed immediately subsequent to the read-out from the S_{nj} stage in order to make available this S_{nj} stage for storage of a subsequent binary information bit. Furthermore, associated memory element M_{nj} is reset, thus indicating stage S_{nj} to be empty, and will remain in this condition until circuit C_j subsequently enters a new binary bit of information into stage S_{nj} . The delay R_n may not be necessary if the switching time of a trigger is large compared to the read-out time therefrom.

The operation of the embodiment shown in FIGURE 4 will now be described, with particular reference to part A of the chart of FIGURE 6. Part A indicates the contents of each of the register stages S_{nj} at respective times during the skew correcting cycle when the particular binary bit configuration of FIGURE 3 is being sensed. In this case, there are only four channels in FIGURE 4, with each channel containing four register stages S_{1j} through S_{4j} . The sequence in which information is placed therein is represented by the numerals 0 through 26 appearing horizontally above the chart. It will be noted that the numerals 0 through 26 appearing in the Part A of FIGURE 6 correspond to the sequence in which the individual bit positions are sensed in FIGURE 3. Furthermore, the bold face numerals in the body of the chart indicate the presence of binary 0 or 1 information bits (the stage being considered filled), while a light face numeral 0 indicates that a register stage is empty. Thus, although the reset condition of a register stage can signify two possible conditions, the distinction is evident in the chart of FIGURE 6. A horizontal arrow running from left to right is a short hand notation indicating that the condition of a register stage is that represented by the numeral immediately to the left of the arrow stem. Where the arrowhead extends into a numbered sequence block

in which there is also a light face numeral 0, this indicates that the register stage is immediately reset to an empty condition during the latter part of the block interval.

It is assumed that in FIGURE 4 that a clear signal is initially applied via conductor 64 to reset all of the register and memory stages S_{nj} and M_{nj} . All of the circuits C_j are reset so that each energizes its output conductor 1. This conditions AND gates A_{11} through A_{14} in order that respective register stages S_{11} through S_{14} may receive the respective track 1, 2, 3, and 4 bits of the first character 12 to be sensed by the transducers in FIGURE 3. The first bit sensed is that of character 12 in track 1, which is supplied by the channel 1 information conductor 60₁ and passes through AND gate A_{11} . Since this bit is a binary 1, stage S_{11} is set. A synchronizing pulse on 61₁ likewise sets element M_{11} and steps circuit C_1 to a state of 2. The second information bit sensed by the transducers is the track 1 bit of character 14, which is a binary 0. Although no signal at this time is applied to conductor 60₁ a synchronizing pulse appears on 61₁ to set element M_{21} and step circuit C_1 to a state of 3. The third bit sensed by the transducers is the track 2 bit (0) of character 12, which fails to set S_{12} but provides a synchronizing pulse to the channel 2 conductor 61₂ (not shown in FIGURE 4) to set memory element M_{12} and step circuit C_2 to a state of 2. In like fashion, the 4th, 5th, 6th, 7th, 8th, and 9th bits sensed by the transducers in FIGURE 3 are applied to their respective channels and register stages 30 therein in a manner similar to that described above.

After the 9th bit has been sensed, which is the track 3 bit of character 14, memory elements M_{11} through M_{13} are now set, indicating that the track 1, 2, and 3 bits of character 12 are contained in register stages S_{11} through S_{13} . However, no output signal is yet generated from gate D_1 . Upon the track 4 bit (1) of character 12 being sensed by transducer T_4 , register stage S_{14} and memory element M_{14} are both set, with circuit C_4 being stepped to a state of 2. AND gate D_1 now detects coincidence of outputs 40 from all of the memory elements M_{11} through M_{14} so as to generate a signal therefrom. This signal gates out all four bits comprising character 12 from the respective register stages S_{11} to S_{14} , and applies them to their respective output OR gates F_1 through F_4 . At approximately 45 the same time, register stages S_{11} through S_{14} and elements M_{11} through M_{14} have pulses applied to their reset terminals by AND gate D_1 . As noted in FIGURE 6, Part A, the signals appearing from OR gates F_1 through F_4 at sequence 10 have the respective configuration 1011, thus 50 representing the complete character 12 shown in FIGURE 3.

The 11th information bit sensed in FIGURE 3 is the track 1 bit of character 20, which may now be placed in the newly emptied register stage S_{11} . It will be noted that 55 the 7th bit sensed in FIGURE 3 was previously placed in register stage S_{41} , whereupon circuit C_1 was stepped and recycled to its initial state of 1. However, it is seen that before this bit of character 20 can be placed in register stage S_{11} , the track 1 bit of character 12 must be read and S_{11} emptied in order to prevent destruction of information. Therefore, at least four register stages are required in channel 1 when sensing the bit pattern in 60 FIGURE 3. Because of the parallel read-out from correspondingly numbered register stages in each channel, each of the other channels also requires an equal number 65 of stages, although it is evident that channel 4 will only have one of its register stages filled at a time when sensing a pattern like that in FIGURE 3. If the pattern changes, however, such that the direction of skew is reversed, then channel 4 may be required to store more 70 bits than channel 1.

The operation of FIGURE 4 is deemed to be obvious in view of the above description, so that the further sensing and entry of information bits into the skew correcting channels will not be described in detail. As seen in FIG-

URE 6, Part A, read-out from the register stages for characters 12, 14, 16, 18, 20, etc., occurs at respective intervals 10, 14, 18, 22, 26, etc.

FIGURE 5 of the drawings shows a slightly different arrangement from that in FIGURE 4, which avoids the use of the individual circuits C and thus is a more economic configuration when a large number information tracks and/or skew digits are encountered. In FIGURE 5, the use of N number of register stages S_{nj} enable the correction of $N-2$ digits of skew. Those triggers and logical gates in FIGURE 5 which have functions similar to those in FIGURE 4 are indicated by corresponding letters and subscripts. Both set and reset output signals from the memory elements M_{nj} are utilized, such that each element M_{nj} has a role to play in its reset as well as its set condition. Thus, each memory element M_{nj} has its reset output terminal connected to AND gate A_{nj} of its corresponding register stage S_{nj} . Furthermore, the set output terminal of each memory element M_{nj} is connected to AND gate $A_{(n+1)j}$ which in turn is connected to the set terminal of register stage $S_{(n+1)j}$. The set output terminal of M_{nj} is also connected to AND gate $B_{(n+1)j}$ of memory element $M_{(n+1)j}$ through a small delay $O_{(n+1)j}$. For example, in channel 1 of FIGURE 5, the reset output terminal of element M_{11} is connected to AND gate A_{11} , while its set output terminal is connected both to AND gate A_{21} , and through O_{21} to the input of AND gate B_{21} . These two connections of the M_{nj} element set output terminal are in addition to its connection with AND gate D_n . It will further be noted that the set output terminal of the last memory element M_{Nj} in each channel is connected to the appropriate AND gates A_{1j} and B_{1j} of the S_{1j} and M_{1j} triggers, inasmuch as the value $(N+1)$ results in the value 1 because of the recycling action.

The purpose of the additional memory trigger connections in FIGURE 5 is to eliminate the need for individual circuits C_j of FIGURE 4. This is accomplished by requiring each of the AND gates A_{nj} to be conditioned by both the reset output of its associated memory element M_{nj} and the set output of the memory element $M_{(n-1)j}$ associated with the immediately preceding filled stage $S_{(n-1)j}$. Furthermore, to set a memory element M_{nj} requires that its associated AND gate B_{nj} be conditioned by the set terminal of the immediately preceding memory element $M_{(n-1)j}$. The use of the delay elements O_{nj} is to insure that only one trigger M_{nj} can be set by a sync pulse, inasmuch as this pulse may have a duration sufficient to overlap the signal appearing on the set output terminal of a memory element which it has itself set. Thus, if element M_{11} is set by a particular sync pulse, the signal from its set output terminal will not arrive at AND gate B_{21} until this particular sync pulse has disappeared. This insures that element M_{21} will not be set until its associated register stage S_{21} is filled with the proper information. It is also to be noted that a delay element K_j can be provided in each channel sync conductor to insure that no switching of the memory elements is performed until after information has been placed into one of the register stages S_{nj} via the information conductor 60_j . This may be necessary if the switching time of the triggers is quite rapid, because the set and reset state configurations of the memory elements must condition only one of the input AND gates A_{nj} during the presence of an information bit signal in order to avoid the insertion of the same bit in two or more register stages. Although no delay such as K_j has been shown in FIGURE 4, it is to be understood that such may be necessary for the same reasons.

Another difference in FIGURE 5 from that of FIGURE 4 is in the use of AND gates D_n for resetting the register and memory elements. As shown in FIGURE 4, the output of each comparison gate D_n is used to reset both its associated register stage S_{nj} and memory element M_{nj} . However, FIGURE 5 shows that the output from each of the AND gates D_n is used to reset register stages

$S_{(n-1)}$ through $S_{(n-1)j}$, and elements $M_{(n-1)1}$ through $M_{(n-1)j}$. For example, the output from AND gate D_2 is applied to reset terminals of register stages S_{11} and memory element M_{11} via respective OR gates H_{11} and G_{11} . The output from AND gate D_1 is likewise applied to reset S_{11} and M_{11} . It will therefore be seen that a signal generated from AND gate D_n is maintained until a signal is generated from the next higher AND gate D_{n+1} , at which time the memory elements M_{n1} through M_{nj} are reset. As long as a gating signal from gate D_n exists, the register stages $S_{(n-1)1}$ through $S_{(n-1)j}$ and elements $M_{(n-1)1}$ through $M_{(n-1)j}$ cannot be set. For this reason then, N pairs of register stages S and memory elements M are required to correct a maximum number of skew digits equal to $N-2$. If the circuit of FIGURE 5 is used to correct the skew of the bit pattern shown in FIGURE 3, in which the maximum number of skew digits is equal to 4, then each channel of FIGURE 5 must contain six register stages S and six associated memory stages M . The operation of FIGURE 5 will now be described in detail with particular reference to the bit pattern in FIGURE 3 and part B of FIGURE 6. In FIGURE 6, part B is physically adjacent to part A so that the difference in operation between FIGURE 4 and FIGURE 5 may be appreciated, inasmuch as both circuits are used to correct skew in the same bit pattern. However, Part B also makes use of the register stages S_5 and S_6 in each channel, because of the requirement that six such stages are necessary to correct for four digit skew. The sequence intervals in part B of FIGURE 6 have the same significance as those shown in Part A of FIGURE 6, and refer to the sequence in which each information bit in FIGURE 3 is sensed by the transducer group. The dark face numbers indicate the value of the binary bit considered stored in each register stage during the operation, while the light face numerals 0 indicate that a register stage is considered empty. Initially, a clear pulse is applied via conductor 64 to reset all of the register and memory triggers in each channel. Then, a start pulse is applied via conductor 65, in order to set each of the memory elements M_{61} through M_{64} via respective OR gates P_{61} through P_{64} . Although the setting of these particular memory triggers at this time provides an output from AND gate D_6 due to coincidence of all inputs thereto, no significant outputs are derived from read-out gates E_{61} inasmuch as their associated register stages S_{61} through S_{64} are in their reset condition. The setting of triggers M_{nj} is necessary in order to condition AND gates A_{11} through A_{14} to pass the first information bit appearing on each of the information input conductors 60_1 through 60_4 . Triggers M_{11} through M_{14} are in their reset state. The first information bit to be sensed is the track 1 bit (1) of character 12 in FIGURE 3, which is applied to conductor 60_1 along with an associated sync pulse on conductor 61_1 . Since only AND gate A_{11} is conditioned in channel 1 at this time, this 1 bit is inserted into register stages S_{11} . Immediately thereafter, the synchronizing pulse is applied via K_1 to one input of AND gate B_{11} . Inasmuch as memory trigger M_{61} has previously been set, B_{11} is conditioned to pass this synchronizing pulse to place trigger M_{11} in its set condition, thus indicating that its associated register stage S_{11} now contains binary information. The placing of M_{11} in a set condition causes a signal to be applied to AND gate A_{21} to which is further applied a signal from the reset terminal of memory element M_{21} . The setting of trigger M_{11} occurs after the track 1 bit of character 12 disappears, but AND gate A_{21} will now be conditioned to receive the track 1 bit of character 14. The set output of M_{11} also passes through a small delay O_{21} in order to condition AND gate B_{21} to pass the synchronizing pulse appearing next on conductor 61_1 which is that associated with the track 1 bit of character 14. Although memory element M_{61} is not reset immediately subsequent to the filling of register S_{11} , it will be noted that no further information can be entered

into stage S_{11} because the reset output of M_{11} is now absent.

Upon transducer T_1 sensing the track 1 bit (0) of character 14, a similar operation occurs in that this bit is effectively placed in stage S_{21} by maintaining same in its reset condition and by setting the associated memory element M_{21} . Information bits sensed at intervals 3 through 9 in FIGURE 3 are likewise placed in their respective channel register stages in the manner indicated above. Upon sensing the track 4 bit of character 12 at interval 10, both register stage S_{14} and element M_{14} are set. And gate D_1 therefore detects coincidence of all its input signals and provides a gating output signal to read-out register stages S_{11} through S_{14} via their respective read-out gates E_{11} through E_{14} . At the same time, the output from D_1 is applied to the reset terminals of all of the register stages S_{61} through S_{64} , and to the memory elements M_{61} through M_{64} . Although the register stages S_6 are already in their reset condition, the memory elements M_6 are reset to discontinue an output from AND gate D_6 . It may therefore be seen from part B of FIGURE 6 that the first character 12 is gated from the skew correcting circuits at interval 10, corresponding with the time in which the same character is gated in FIGURE 4.

The track 1 bit of character 20 sensed at time 11 in FIGURE 3 is now inserted into register stage S_{51} in FIGURE 5, instead of into stage S_{11} as in FIGURE 4. Further, the track 1 bit of character 22 is placed in register stage S_{61} instead of into stage S_{21} . However, prior to the sensing of the track 1 bit of character 22, the track 4 bit of character 14 has been sensed, which thus causes AND gate D_2 to reset memory elements M_{11} through M_{14} . Therefore, by the time that a bit is available for insertion in stage S_{61} , the signal from AND gate D_1 has disappeared so that it no longer is applied to the reset terminal of state S_{61} . A similar condition is observed at the time that the track 1 bit of character 24 is sensed, inasmuch as the output from AND gate D_2 has been terminated due to the read-out of character 16 from register stages S_{31} through S_{34} .

It should therefore be appreciated that the mode of operation of FIGURE 1, as exemplified by FIGURES 4 and 5, provides register stages in each channel having both parallel read-in and read-out gates for holding corresponding order bits of successive characters, until all bits of a particular character are stored in the circuit. Means are provided in each of the embodiments of FIGURE 4 and 5 to determine when corresponding register stages in each channel have been filled with information, so that they may then be examined. In FIGURE 4, the circuits C provide the loading sequence for the register stages, while registers M provide merely a memory function. In FIGURE 5, however, the combination of the set and reset conditions of memory elements M provide the sequence function, with the set condition of elements M providing memory.

FIGURE 2 of the drawings shows a second embodiment of the present invention having a slightly different mode of operation from that shown in FIGURE 1 and by FIGURES 4 and 5. As in FIGURE 1, the dark lines in FIGURE 2 indicate information paths, while the light lines indicate paths for control signals. Binary bits sampled by each transducer in FIGURE 3 are applied in serial fashion to information channels 70_j , while synchronizing pulses associated with binary bit intervals are applied on conductors 71_j . A group of read-in gates 72_j accepts the serial information bits on conductor 70_j and selectively places each in a respective one of a plurality of register stages 73_j as is indicated by the multiple conductor cable N connected between gates 72_j and register stages 73_j . The particular register stage selected is determined by the condition of a sequence circuit 74_j which is changed by each synchronizing pulse on conductor 71_j . In this respect, the circuit of FIGURE 2 is the same as that shown in FIGURE 1, inasmuch as a serial train

of information bits appearing from a track transducer is placed in selected channel register stages in parallel fashion.

Read-out of information from a group of register stages 73_j is accomplished from only one particular stage therein. This is indicated by the single output conductor. The stages 73_j are therefore connected together as a shift register so that an information bit placed in any register stage N therein may be successively shifted from stage to stage until it eventually reaches the read-out stage. The shifting operation is controlled by means of a single conductor from a single comparison gate 75 having inputs derived from a single memory element 76_j in each of the channels. Each memory element 76_j is associated merely with the terminal read-out stage in its channel, and by its setting indicates that this stage is filled with information and ready for interrogation. The sequencer 74_j must also take into account the fact that after each shift operation, the register stage last filled by it is now empty because its bit information is transferred to the adjacent register stage in the direction of the shift. Therefore, sequencer 74 must be conditioned to place the next information bit following a shift operation into this now empty register stage. This procedure prevents any empty stages from occurring between filled stages.

As long as the read-out stage of group 73_j is filled with information, whether it be placed there from read-in gates 72 or from the adjacent register stage during a shift operation, memory element 76 maintains an output to the single comparison gate 75 . Thus, when the read-out stage in each of the channels is filled with information, an output from comparison gate 75 causes said channel read-out stages to be sensed for their information. At the same time, information bits held in the other register stages are shifted one position so as to replace said information in the read-out stage with a new bit. If there are no information bits held in the adjacent stages of a channel, then a shift operation in that channel will result in the read-out stage being reset to an empty condition. In this case, its associated memory element 76_j indicates the empty condition and so deconditions the comparison gate 75 until information is placed into the read-out stage via conductor 70_j .

It may therefore be seen that the binary bits read from a channel register group all appear on the channel output conductor in the same sequence observed on the storage track associated with the channel. For example, the track 1 bits of characters 12, 14, 16, 18, etc. appear in that order from the channel 1 read-out register stage during successive read-out times. Since all channel read-out stages are sampled during a read-out time, then the bits read therefrom must belong to and comprise the same character. It is not necessary in the embodiment of FIGURE 2, however, that each channel contain the same number N of register stages if the skew angle of the sensed bit pattern is assumed to remain relatively constant. For example, as can be seen from FIGURE 3, the maximum number of register stages filled at any time in each of the channels 1, 2, 3, and 4 is four, three, two, and one, respectively. Since each sequencer begins to fill its associated empty register stages in order commencing with the read-out stage, then only one stage would ever be used in a channel responsive to track 4 bits of FIGURE 3, while two and three stages are needed only in channels 3 and 2, respectively. However, if the skew angle is expected to be variable, then the number of register stages in the outer channels should be sufficient to handle all of the anticipated conditions, although the number of stages in the center channels normally may be less. For these reasons, then, the letters N in FIGURE 2 have channel subscripts associated therewith to indicate possible different values.

FIGURE 7 of the drawings shows the details of an embodiment having the mode of operation illustrated in the block diagram of FIGURE 2. Each channel of the

skew correcting circuit includes a group of register stages S_{1j} through S_{Nj} for the storage of successive information bits arriving on input conductor 80_j . However, as indicated above, each channel need not necessarily contain the same number N of register stages S . Therefore, subscripts are utilized with each letter N in order to indicate that the number of stages and read-in gates may differ in each channel. A forward backward sequence circuit Z_j is associated with each channel to determine into which stage S_n an information bit is to be placed. A group of input AND gates W_{1j} through W_{Nj} is provided each of which is selectively conditioned by one of the outputs from the circuit Z_j to pass therethrough an information bit occurring on conductor 80_j . Each circuit Z_j has a "step forward" input which, upon receipt of synchronizing pulses, advances the circuit in one direction. A "step backward" input is also provided which, upon receipt of a read-out pulse, steps the sequence circuit in the opposite direction. A clear input to each circuit is also provided for resetting same to a reference state of prior to the sensing of characters from the storage medium. A sequence circuit may be forward-backward counter, a reversible shift register, or many other different kinds of reversible commutator which can be found in the prior art.

Emerging from each circuit Z_j are two leads 1 and $\bar{1}$ respectively, indicating an internal state of 1 or state other than 1. When circuit Z_j has a signal on its output lead 1, thus conditioning its associated register stage S_{1j} to receive an information bit via AND gate W_{1j} , then no signal appears on output $\bar{1}$. However, upon circuit Z_j producing an output on any other lead besides 1, then a signal appears on its $\bar{1}$ lead. Therefore, a signal from terminal $\bar{1}$ indicates that stage S_{1j} has been filled.

Each $\bar{1}$ conductor from circuit Z_j is applied to a common AND gate Y which is conditioned to generate an output only when signals appear on all of its inputs, thus indicating that all stages S_{11} through S_{1j} have information bits therein. The output from AND gate Y is applied to a set of read-out gates L_{11} through L_{1j} which sample the contents of their associated register stages S_{11} through S_{1j} . The output from AND gate Y is also directed to the reset terminals of each of the register stages S_{nj} in all of the channels via a set of OR gates U_{nj} . For example, the output from AND gate Y is directed to OR gates U_{11} through U_{N1} . Therefore, each register stage in a channel is reset upon occurrence of coincident signals at AND gate Y , while the readout stages S_{11} through S_{1j} in each channel are sampled and their contents fed to further utilization circuitry not shown. At the same time that the register stages S_{nj} are reset, the output signal from gate Y also is applied to a series of read-out AND gates L_{2j} associated with the remaining register stages S_{2j} through S_{Nj} in each channel. The output from each of these read-out AND gates is applied to the set input of the adjacent register stage $S_{(n-1)j}$ via a set of OR gates Q_1 through $Q_{(N-1)}$. Each group of register stages S_{nj} in each channel is therefore connected in shift register fashion such that upon the occurrence of a signal from AND gate Y , all the information bits in a register stage group are shifted right.

A delay unit I_{nj} is associated with and is individual thereto each of the stages S_{1j} through $S_{(N-1)j}$, and is connected between the output of AND gate $L_{(n-1)j}$ and one of the inputs to OR gate Q_{nj} . Its purpose is to insure that the stage S_{nj} is reset to its empty condition prior to the entrance of a 1 bit from stage $S_{(n+1)j}$. Furthermore, although not specifically shown in FIGURE 7, a group of delay units similar to R_{nj} in FIGURE 4 might be necessary to insure that each stage S_{nj} is sampled at AND gate L_{nj} prior to being reset by the signal from AND gate Y . Likewise, if the response time of circuit Z_j is quite rapid when pulsed at its "step forward" terminal by a sync pulse, a delay similar to delay K_j in FIGURE 5

may be necessary to insure that circuit Z_j does not change stages until after the information bit has been placed into the appropriate register stage. It may therefore be appreciated that the only register stage in a channel from which information is retrieved is the first stage S_{1j} into which all bits will eventually be placed prior to their extraction therefrom.

At the same time that a shift operation is initiated in a register stage group, the forward-backward circuit Z_j must be controlled such that it will subsequently condition the read-in gate W_{nj} of the unfilled stage S_{nj} nearest stage S_{1j} . For example, if information bits in channel 1 are contained only in stages S_{11} , S_{21} , and S_{31} immediately prior to a shift operation, then stage S_{31} will be empty immediately subsequent thereto because it will have received no information from the adjacent stage S_{41} . In such an event, an information bit subsequently appearing on conductor 81_j should be inserted into now empty stage S_{31} . If counter Z_j happens to be resting in a state of 4 at the time of shifting, then it must be stepped in a reverse direction to return to a count of 3 in order to so condition AND gate W_{31} . Since shift operations occur simultaneously in all channels, each counter Z_j must be similarly controlled. Therefore, the output from AND gate Y is applied to all of the "step backward" terminals of the counters Z_j so as to condition each to insert a subsequent information bit into the right most unfilled register stage.

Since certain binary patterns on the storage medium can result in the simultaneous sensing of information bit areas in two or more tracks, there might be occasions when either an information bit or conductor 80_j or a "step forward" pulse to circuit Z_j appears simultaneously with a "shift" and "step backward" pulse from AND gate Y . Such would be the case, for example, if the track 3 bit of character 16 and the track 4 bit of character 14 both pass under respective transducers T_3 and T_4 at about the same time, with the latter being the final sensed bit of character 14 so that read-out thereof can occur. To avoid the situations where a sequencer Z_j is apt to be stepped backward in the middle of inserting information into a stage S_{nj} , or where said sequencer may have pulses applied concurrently to its two inputs, circuitry is provided in FIGURE 7 to clock the information and sync pulses at a time different from that in which a shift pulse appears. AND gates X_j and V_j are provided in each channel for the information conductor 80_j and sync conductor 81_j , respectively. A source 84 generates two trains of clock pulses with one being 180° out of phase with the other, such as indicated by OA and OB. The positive portions of the phase B(OB) clockpulses are used to condition gates X_j and V_j in each channel to pass all or a portion of a signal appearing on their associated input conductors. For this reason, the frequency of the clockpulse trains should be rather high so that a positive cycle thereof is bound to overlap once a signal representing an information bit and/or sync bit in order to allow same to activate a trigger S_{nj} and sequencer Z_j . However, the frequency should not be so high as to cause the OB train to sample the same signal more than once. The phase A(OA) clockpulse train is used to condition AND gate Y to generate a signal if all other inputs thereto from the $\bar{1}$ sequencer outputs are also present. Because the OB train is out of phase with the OA train, there is no chance that a "shift" and "step backward" pulse from gate can occur at the same instant that pulses are applied to a trigger S_{nj} or to the "step forward" terminal of sequencer Z_j .

The operation of FIGURE 7 will now be briefly described with reference also being made to FIGURE 8 of the drawing which shows the contents of each register stage S_{nj} at different intervals when the binary pattern of FIGURE 3 is being scanned. The legend of FIGURE 8 is the same as that described for FIGURE 6. Initially, a clear pulse is applied to conductor 82 to reset

sequences Z_1 through Z_4 to a state of 1, whereupon AND gates W_{11} through W_{14} are conditioned to receive information bit pulses (representing binary 1's from the pattern) at phase OB times via conductors 80_1 through 80_4 , respectively. The first bit to be sensed is the track 1 bit of character 12 which is thereupon placed in S_{11} and whose associated sync pulse steps sequence circuit Z_1 to a state of 2. The $\bar{I}$ conductor of Z_1 thus has a signal generated thereon.

The operation of the channel circuits continues as described above for the sensing of the second through ninth bits in FIGURE 3, where said ninth bit is the track 3 bit of character 14. Up to and including this interval, not all of the Z_j circuits have as yet been stepped from the state of 1, so that not all inputs have been applied to AND gate Y as is required. Upon the track 4 bit of character 12 being sensed, it is placed in S_{14} and Z_4 subsequently stepped to a state of 2. Thereupon, signals are applied to all of the $\bar{I}$ inputs to AND gate Y, and upon the next subsequent positive cycle of the OA clock-pulse train, a signal is generated therefrom. This signal reads out the bits of character 12 from register stages S_{11} , S_{12} , S_{13} , and S_{14} via respective AND gates L_{11} , L_{12} , L_{13} , and L_{14} . A shift right operation is also performed during which the following occurs: in channel 1, the track 1 bit of character 14 moves from S_{21} to S_{11} , the track 1 bit of character 16 moves from S_{31} to S_{21} , and the track 1 bit of character 18 moves from S_{41} to S_{31} ; in channel 2, the track 2 bit of character 14 moves from S_{22} to S_{12} , and the track 2 bit of character 16 moves from S_{32} to S_{22} ; in channel 3, the track 3 bit of character 14 moves from S_{23} to S_{13} ; and in channel 4, stage S_{14} is reset to zero with no information being placed therein from S_{24} .

Immediately prior to the above signal from AND gate Y, sequencers Z_1 , Z_2 , Z_3 , and Z_4 have respective state of 1, 4, 3, and 2. Z_1 is in state 1 because of recycling from state 4 to state 1; however, its range could be increased to include five states if desired. When the above mentioned pulse is generated from AND gate Y, then each circuit Z_1 through Z_4 is stepped once in reverse, resulting in new states of 4, 3, 2, and 1, respectively. This causes the $\bar{I}$ signal from Z_4 to disappear which consequently results in AND gate Y being de-energized. The track 1 bit of character 20 will subsequently be placed in now empty stage S_{41} . In view of the above, the further operation of FIGURE 7 is thought to be obvious.

While preferred embodiments of the invention have been shown and described, it is obvious that many modifications can be made thereto without exercise of invention by one skilled in the art. For example, by providing additional stages in FIGURE 4 over and above the number required for maximum pattern skew, the output of a gate D_n might be used to gate out other filled register stages besides S_n .

Thus, the intended scope of the present invention is to be ascertained from the appended claims.

We claim:

1. A circuit for aligning successive sets of related binary information signals where each of said signals appears on a different one of a plurality of information channels and is also accompanied by a synchronizing signal appearing on an associated synchronizing channel, said circuit comprising the combination of: a N stage register for each information channel separate, sequence means for each information channel selectively settable to transfer each binary information signal thereon into register for each information channel, separate sequence means setting, said sequence means being connected with the associated synchronizing channel so as to have its setting changed in one direction by each synchronizing signal appearing on the associated synchronizing channel, separate first means for each information channel and individual solely thereto to indicate that a register stage

thereof is filled with binary information, second means common to all of said channels and responsive to a coincidence of related first means indications one from each channel to generate a readout indication, and third means responsive to the said readout indication to read out the binary information stored in related filled register stages one in each channel.

2. A circuit according to claim 1 in which said read-out related channel register stages are respectively associated with the said related first means.

3. A circuit according to claim 1 wherein each of said channel first means comprises a group of two state elements each associated with a different one of said channel register stages, and each responsive to the setting of said channel sequence means and to a synchronizing pulse for being set to a state indicating the fill of its associated register stage, and said second common means comprises a group of coincidence detecting means each associated with a different set of related two-state elements in different channels.

4. A circuit according to claim 3 in which the said readout related channel registers are respectively associated with the set of related two-state elements whose coincident indications cause said read-out to occur.

5. A circuit according to claim 1 wherein each of said channel first means comprises a group of two state elements each associated with a different one of said channel register stages and each indicating the fill thereof when in a second state, each of said channel sequence means includes said group of two-state elements together with a group of gate means each being responsive to a first state of one element and a second state of another element for gating in a binary information signal to the associated register stage of said one element, with each gate means also being responsive to the second state of said another element and a synchronizing signal for setting said one element to its second state, and said second common means comprises a group of coincidence detecting means each associated with a different set of related two-state elements.

6. A circuit according to claim 5 in which the said read-out related channel registers are respectively associated with the set of related two-state elements whose coincident indications cause said read-out to occur.

7. A circuit according to claim 2 wherein each of said channel multistage registers is connected as a shift register, each of said channel sequence means is adapted to have its setting changed in the opposite direction, each of said channel first means comprises a single means associated with only one register stage of its associated shift register, said second common means includes one coincidence detecting means associated with all of channel first means, and means are further provided in each channel to shift information in said shift register while changing the setting of said channel sequence means in the opposite direction each time that said one register stage is read out.

8. A circuit according to claim 7 wherein the number of register stages may vary in different channels.

9. A circuit for aligning successive sets of related binary information signals where each of said signals appears on a different one of a plurality of information channels and is also accompanied by a synchronizing signal appearing on an associated synchronizing channel, said circuit comprising the combination of: a multi-stage register for each information channel, sequence means for each information channel selectively settable to transfer each binary information signal thereon into any one of said register stages according to said sequence means setting, said sequence means being connected with the associated synchronizing channel so as to have its setting changed by each synchronizing signal appearing on the associated synchronizing channel, a group of two state elements for each information channel, with each element of a group being associated with a different one of said

channel register stages to indicate that said register stage is filled with binary information, a group of coincidence detection means each associated with a different set of related two state elements one in each of said channels, where each detection means is responsive to a coincidence of indications from all of its associated elements to read out the binary information stored in related filled register stages one in each channel.

10. A circuit according to claim 9 in which said read-out related channel registers are respectively associated with the set of related two-state elements whose coincident indications cause said read-out to occur.

11. A circuit according to claim 10 wherein an output from a coincidence detector associated with a set of related two-state elements is also used to subsequently clear the channel register stages associated with said set.

12. A circuit for aligning successive sets of related binary information signals where each of said signals appears on a different one of a plurality of information channels and is also accompanied by a synchronizing signal appearing on an associated synchronizing channel, said circuit having for each of said channels, a multi-stage register, a group of two-state elements each associated with a different one of said channel register stages, a first group of gate means each being responsive to a first state of one element and a second state of another element for gating in a binary information signal to the associated register stage of said one element, a second group of gate means each being responsive to the second state of said another element and a synchronizing signal for setting said one element to its second state thus indicating the fill of its associated register stage, said circuit also having in common with all of said channels a group of coincidence detection means each associated with a different set of related two-state elements one in each of said channels, where each detection means is responsive to a coincidence of second state indications from all of its associated elements to read out the binary information stored in related filled register stage one in each channel.

13. A circuit according to claim 12 in which said read-out related channel register stages are respectively associated with the set of related two-state elements whose coincident indications cause said read-out to occur.

14. A circuit according to claim 13 in which the output from a coincidence detector associated with a set of related two-state elements is also used to clear the channel register stages associated with a different one of said sets.

15. A circuit for aligning successive sets of related binary information signals where each of said signals

appears on a different one of a plurality of information channels and is also accompanied by a synchronizing signal appearing on an associated synchronizing channel, said circuit having, for each of said channels, a N-stage shift register having one read-out stage therein in the direction of shift a reversible sequence means selectively settable to directly transfer each binary information signal on said read channel into any one of said register stages beginning with said read-out stage according to said sequence means setting, said sequence means being connected with the associated synchronizing channel so as to have its setting changed in a forward direction by each synchronizing pulse, means to indicate when said read-out stage is filled with binary information, said circuit also having in common with all of said channels a single coincidence detecting means associated with each of said channel indicating means and responsive to a coincidence of indications from all to read out the binary information from said channel read-out stages, to initiate one shift step in each of said channel shift registers, and to change the sequence means setting in a reverse direction.

16. A circuit according to claim 15 in which the number N of register stages may vary in different channels.

17. A circuit according to claim 15 wherein interlock means are further provided to prevent the simultaneous occurrence of both a shift operation and a register stage read-in operation, said last mentioned means further preventing the simultaneous occurrence of both a sequence means forward change and a sequence means reverse change.

18. A circuit according to claim 17 wherein said interlock means includes a clockpulse source generating first and second clock pulse trains of the same frequency but one-half cycle out of phase with each other, gating means in each of said information and synchronizing channels conditioned by said first clockpulse train, with said coincidence detecting means being conditioned by said second clockpulse train.

19. A circuit according to claim 18 in which the number N of register stages may vary in different channels.
